(57) **CLAIM**

I claim the ornamental design of a mini USB rotatable hub, as shown.

DESCRIPTION

FIG. 1 a top, front right-side perspective of my new design for a mini USB rotatable hub,

FIG. 2 a rear elevation thereof,

FIG. 3 a front elevation thereof,

FIG. 4 a right-side elevation thereof,

FIG. 5 a left-side elevation thereof,

FIG. 6 a top plan view thereof; and,

FIG. 7 a bottom plan view thereof.
